UNITED STATES PATENT OFFICE.

ALBERT G. CARLING, OF NEW YORK, N. Y.

DESIGN FOR A BOTTLE.

48,151.

Specification for Design. Patented Nov. 16, 1915.

Application filed July 27, 1915. Serial No. 42,227. Term of patent 14 years.

To all whom it may concern:

Be it known that I, ALBERT G. CARLING, a citizen of the United States, residing in the city of New York, borough of Manhattan, in the county and State of New York, have invented a new, original, and ornamental Design for a Bottle, of which the following is a specification, reference being had to the accompanying drawings, forming part thereof.

Figure 1 is a front elevation of the bottle

showing my new design; Fig. 2 is an edge view of the same; and Fig. 3 is a cross section of the same.

I claim:

The ornamental design for a bottle as shown.

ALBERT G. CARLING.

Witnesses:

THEO. G. HOSTER,
PHILIP D. ROLLHAUS.
